Primary Examiner — Jennifer L Rempfer*Assistant Examiner* — Aaron C Fowler(74) *Attorney, Agent, or Firm* — Crowell & Moring LLP(57) **CLAIM**

The ornamental design for a wheel or wheel cover, as shown and described.

DESCRIPTION

FIG. 1 is a perspective view of a first embodiment of a wheel or wheel cover according to the design; and

FIG. 2 is a front view thereof.

FIG. 3 is a perspective view of a second embodiment of the wheel or wheel cover according to the design; and,

FIG. 4 is a front view thereof.

The broken lines in the drawings illustrate environmental subject matter only and form no part of the claimed design.
